UNITED STATES PATENT OFFICE

EINAR MORTERUD, OF TORDEROD, NEAR MOSS, NORWAY

ARRANGEMENT FOR THE CIRCULATION OF DIGESTING LIQUOR IN WOOD PULP
DIGESTERS

Application filed November 24, 1930, Serial No. 497,898, and in Norway May 14, 1929.

- The present invention relates to an arrangement for circulating the digesting liquor in wood pulp digesters and has for its object to provide an arrangement, by means of which 5 the circulation of the liquid will take place evenly throughout the digester, whereas at the same time the arrangement will not form an obstruction to the emptying of the digester after the digesting process.
- 10 The invention relates to the kind of digesters which are provided between the lower and upper end with an interior or exterior conduit, comprising a pump serving to circulate the liquor either from the top of the 15 digester to the bottom thereof or in the opposite direction.
- In accordance with the invention the sieve connected with the circulation pipe near the lower end of the digester is located co-axially 20 with the digester without having any connection with the conical bottom part of the same.
- By this arrangement it is obtained in the first instance that the liquid passing upwards or downwards through the digester is evenly 25 distributed over the cross section thereof, and secondly pulp and splinters adhering to the sieving surface will not form an obstruction when the digester is to be emptied.
- 30 By giving the sieving surface of the centrally arranged lower sieve in the digester the form of a conical surface it is obtained that all material adhering to the sieve will easily be carried away when the digester is emptied.
- 35 On the drawings two forms of the invention are diagrammatically illustrated.
- In accordance with the form shown on Fig. 1 there is located in the lower part of the 40 digester a sieve 2, having the form of a truncated cone co-axial with the digester and pointing downwards.
- The sieve is mounted on a tube 3, which is 45 attached to a stave 4. Tube 3 leads through the outside of the digester to pump 5, the pressure tube whereof leads to the top of the digester after having passed through a heating apparatus or the like (not shown).
- According to the form of the invention illustrated on Fig. 2 tubes 3 and 6 are both 50 located inside the digester, and are connected to a pump 5, which is also placed in the interior of the digester. Sieve 2 in this form of the invention is also given the form of a cone pointing downwards.
- Claims:
1. In a pulp digester a circulating device 55 for the digesting liquid comprising a tube connecting the lower part of the digester with the upper part thereof, a mechanically driven pump connected with said tube for circulating liquor therethrough, intake and outlet sieves at the lower and upper end of said tube, the sieve connected with the lower end of the tube being located co-axially with the digester and having no connection with the 60 conical bottom surface thereof.
2. In a pulp digester a circulating device 65 for the digesting liquid comprising a tube connecting the lower part of the digester with the upper part thereof, a mechanically driven pump connected with said tube for circulating liquor therethrough, intake and outlet sieves at the lower and upper end of said tube, the sieve connected with the lower end of said tube having a conical sieving surface located 70 at a certain distance away from the conical bottom surface of the digester and co-axially 75 with the same.
- In testimony whereof I affix my signature.
